UNITED STATES PATENT OFFICE.

CHARLES F. MEYERING AND JAMES A. O'CONNOR, OF ROCHESTER, NEW YORK.

FISHERMAN'S PAIL.

SPECIFICATION forming part of Letters Patent No. 400,588, dated April 2, 1889.

Application filed October 18, 1887. Serial No. 252,715. (No model.)

To all whom it may concern:

Be it known that we, CHARLES F. MEYERING and JAMES A. O'CONNOR, both of Rochester, in the county of Monroe and State of New York, have invented a certain new and useful Improvement in Fishermen's Pails; and we do hereby declare that the following is a full, clear, and exact description of the same, reference being had to the drawings accompanying this application.

Our improvement relates to receptacles for holding minnows and other fish, and is designed for fishermen's use, the object being to provide a receptacle in which the minnows can be kept alive without constantly changing the water, and which when not in use can be folded in compact space, so as to be carried in the pocket or in an ordinary fish-basket.

Our invention consists in the construction and arrangement hereinafter described and definitely claimed.

To this end our invention consists, essentially, in the combination of a collapsible or folding frame and a flexible covering for the same, and also in minor features, as will be more fully described and definitely claimed.

In the drawings, Figure 1 is a central vertical section of one form of the receptacle. Fig. 2 is a perspective view of the collapsible or folding frame divested of the flexible covering. Fig. 3 is a section similar to Fig. 1, but showing another form of the receptacle. Fig. 4 is a view similar to Fig. 1, showing a modification. Fig. 5 is a vertical section of Fig. 4 in the closed or folded condition. Fig. 6 is an enlarged vertical section of one corner of Fig. 4. Fig. 7 is a vertical section of the device having the frame made in two folding sections for holding large fish.

A indicates the collapsible spring-frame, and B the flexible reticulated covering. The frame is made to be collapsed or to be closed in compact form when not in use, so as to be carried in the pocket. It may be made in a variety of ways. In Fig. 1 it is shown as made of two head-rings, *a a*, and connecting spring wires or rods *b b*. The natural spring of the wires will throw the rings apart and cause the frame to stand upright. To collapse or fold it, the upper ring is simply turned axially, as indicated by the arrow,

Fig. 2, the spring-wires in that case folding spirally down into a close body as the rings are brought together, a torsional action being produced.

In Fig. 3 the frame is shown as a spiral spring, which in its natural position stands upright, but when pressed down folds or closes in a compact body.

The flexible covering B consists simply of a bag that incloses and covers the frame, being made to open and close at the top by any suitable means, that shown in Figs 1 and 3 being a puckering-spring like that of an ordinary bag. The covering may be made of any flexible material that will hold the fish and will allow the passage of water, and at the same time will fold with the frame. Network is shown in the drawings. Common cloth will answer the purpose. The fish are simply placed in the receptacle and hung over the side of the boat in the water, in which case they will always remain lively and active, and will require no changing or other attention, as they do where they are kept in an ordinary close pail.

When not in use, the device can be folded so compactly as to be carried in the pocket or in an ordinary fish-basket. By this means a fisherman can carry his minnow-pail with him without trouble, and is not inconvenienced as he is when compelled to carry an ordinary pail.

In Figs. 4 and 5 the same arrangement is used as in Fig. 1, with the addition of sheet-metal heads *c d* at top and bottom, the same being flanged and shutting together, like a blacking-box, when the device is closed, as shown in Fig. 5. In such case the spring-wires and the flexible covering fold compactly inside the box, which thus presents a smooth exterior. The upper head is provided with a bail, *f*, and a hinged cover, *g*, by which means access is obtained to the receptacle. The cover is provided with a suitable catch, *h*, by which it is held closed.

Fig. 7 shows a large receptacle for holding large fish which may be caught in fishing, the same being anchored over the side of the boat to keep the fish alive. In such case the collapsible frame is made in two or more sections, *A A'*, each of which folds independently; but all fold in one compact body. In

such case intermediate rings, a' , (one or more,) are used, with which the wires of the contiguous sections engage. The whole is covered by the flexible covering before described, and the flanged heads shown in Fig. 4 may or may not be used, as desired.

In order to remove the receptacle from the water and carry it in the boat in moving from one place to another, and at the same time retain water in the receptacle, a rubber or other water-tight bag is used which is drawn over the receptacle. This rubber bag is indicated by the exterior dotted line, k , in Figs. 1 and 4.

Having described our invention, we do not claim a flexible net with a floating cover placed in a common bucket; but

What we claim as new, and desire to secure by Letters Patent, is—

1. In a fisherman's pail, the combination of a spring-frame consisting of heads and spring-wires connecting them, and a flexible reticulated covering to said frame, the whole forming a receptacle that can be collapsed by turning the upper head axially, as shown and described, and for the purpose specified.

2. In a fisherman's pail, the combination of a spring-frame consisting of heads and spring-

wires connecting them, and a flexible reticulated covering to said frame, the heads being constructed with flanges, so that when the device is collapsed said heads will shut together in box form, as herein shown and described.

3. In a fisherman's pail, the combination of a spring-frame composed of two or more sections, each consisting of heads and spring-wires connecting them, and each folding independently, and a flexible reticulated covering to said frame, the whole forming a receptacle that can be collapsed by turning each section axially, the whole folding in compact form, as herein shown and described.

4. In a fisherman's pail, the combination of a collapsible spring-frame, a flexible covering inclosing the frame, and a water-proof bag inclosing both the frame and covering, in the manner and for the purpose specified.

In witness whereof we have hereunto signed our names in the presence of two subscribing witnesses.

CHARLES F. MEYERING.
JAMES A. O'CONNOR.
